O. F. McENANEY

STEAM TUBE AND PIPING FOR TEXTILE MACHINERY

Filed Dec. 11, 1926

Inventor

OWEN F. McENANEY

By *Arthur L. Sargent*

Attorney

UNITED STATES PATENT OFFICE.

OWEN F. McENANEY, OF BROOKLYN, NEW YORK.

STEAM TUBE AND PIPING FOR TEXTILE MACHINERY.

Application filed December 11, 1926. Serial No. 154,250.

The object of my invention is to provide novel steam tubes and piping for textile machinery such as knitting machines; and particularly to provide a novel construction 5 of steam tube which will more efficiently steam the thread whereby a finer fabric can be produced and the machines can be run faster and more production obtained.

I attain the objects of my invention by 10 the mechanism illustrated in the accompanying drawings, in which—

Figure 1 is a perspective view of my invention applied to textile machinery; particularly spring needle machines;

15 Fig. 2 is a detail longitudinal sectional view of my improved steam tube;

Fig. 3 is a transverse section on line 3—3 of Fig. 2; and

20 Fig. 4 is an end elevation of a modification of the steam tube having a plurality of thread channels 11.

Like numerals designate like parts in each 25 of the several views.

Referring to the accompanying drawings 30 I provide an approximately T-shaped steam tube comprising a vertical cylinder 2 and a horizontal cylinder 9 of approximately the same diameter as the cylinder 1. Cylinder 9 has an opening 8 communicating with the 35 chamber 4 of inner cylinder 2. Inner cylinder 2 has a plurality of apertures 5 communicating with the annular chamber 3. Outer vertical cylinder 1 has an opening 7 into the threaded inlet nozzle 6 by which the steam tube is mounted on pipe 18.

I provide a main pipe line 14 which has a pipe connection 15 with the branch pipe line 16 which in turn has the branch pipes 18 which communicate with and support the 40 steam tubes hereinbefore described and illustrated in Figs. 1 and 2 of the drawings. Branch pipe lines 16 are provided with suitable manually controlled valves 17 as shown in Fig. 1.

45 I provide a suitable supporting bar 21 carrying the wire guide supports 22 which in turn carry the thread guides 23 through which the thread or yarn 25 from bobbin 24 is drawn to guide it to the thread channel 50 11 in the end 10 of the horizontal cylinder 9 of the T-shaped steam tube and thence through the corresponding thread guide 11 of the opposite end 10 as illustrated in Fig. 1. A pipe 13 opens out of the closed bottom 55 end 12 of steam tubes 1 and 2 as shown in

Fig. 2 and is supported on and communicates with the steam discharge pipe 20.

The direction of the flow of steam is indicated by arrows in Fig. 2. The arrangement of the thread to travel horizontally through 60 the steam tube results in a more efficient moistening of the thread with steam with a consequent improvement in the quality of the fabric produced. It also makes it possible to run the machines faster and therefore 65 get more production per machine. Any water condensed in the cylinder 9 flows through opening 8 into the chamber 4 of the inner cylinder 2 and thence through pipe 13 to the discharge pipe 20. The apparatus 70 is especially intended for use on textile machinery used for knitting or weaving fiber silk.

Referring to Fig. 4 of the drawings I may 75 provide tubes having a plurality of thread guides 11 at opposite ends of the horizontal portion or cylinder of the tube to permit of simultaneously operating a plurality of threads through the tube. The tubes can be used for one, two or three threads according 80 to the number of porcelain thread guides 11 used.

What I claim is—

1. A steam tube for use on textile machinery of the class described, comprising a 85 pair of spaced vertical tubes one arranged within the other, a horizontal tube having thread guides mounted in opposite ends thereof, and the inner vertical tube having a plurality of apertures for the flow of 90 steam from the annular chamber surrounding said tube to the interior thereof, said inner tube being in communication at one end with the horizontal tube, and being in communication at the other end with a discharge pipe, and means for the inflow of 95 steam to the annular chamber between the respective spaced vertical tubes.

2. In apparatus for use on textile machinery of the type described, a main pipe line, valve-controlled branch pipe lines in communication with the main pipe line, branch conduits opening out of said branch pipe line, T-shaped steam tubes, nozzles on the upright portions of said T-shaped tubes in communication with the aforesaid branch conduits and permitting of inflow of steam into the T-shaped tubes, the T-shaped tubes having a horizontal cylindrical element having 100 opposite thread channels in the ends 105 110

thereof to permit of the thread traveling horizontally through the horizontal portion of said steam tube, and means for the passage of steam into said tube.

5. In apparatus for use on textile machinery of the type described, a main pipe line, valve-controlled branch pipe lines in communication with the main pipe lines, branch conduits opening out of said branch 10 pipe line, T-shaped steam tubes, nozzles on the upright portions of said T-shaped tubes in communication with the aforesaid branch conduits and permitting of inflow of steam into the T-shaped tubes, the T-shaped tubes 15 having a horizontal cylindrical element having opposite thread channels in the ends thereof to permit of the thread traveling horizontally through the horizontal portion of said steam tube, means for the passage of 20 steam into said tube, and means for the discharge of steam from the lower end of the vertical portion of said tube.

4. In textile machinery of the class described, T-shaped steam tubes having thread 25 guides in opposite ends of the horizontal cylindrical portion of said tube, and having spaced vertical cylinders, the inner cylinder being in communication with the horizontal cylindrical portion of the tube and the 30 outer cylinder being out of direct communication with the horizontal cylinder, and openings in the inner cylinder for the flow

of steam from the outer to the inner vertical cylinder, means for the flow of steam into the outer cylinder, and means for the discharge of the condensed vapor from the 35 lower end of the inner cylinder.

5. In textile machinery of the class described, the combination of T-shaped tubes having a horizontal cylindrical section, said 40 section having a plurality of thread guides at opposite ends thereof, a vertical cylindrical section, an inner cylinder having apertures for the passage of steam from the outer to the inner chamber, said inner 45 chamber being in communication at one end with the horizontal cylinder through which the threads travel, and a discharge pipe at the other end of the vertical inner cylinder with which it communicates for the discharge of condensed vapor, and means for the inflow of steam to the outer vertical cylinder.

6. In combination with the apparatus described in claim 5, a main steam pipe line, 55 branch steam pipe lines in communication with the main steam pipe line, valves for controlling the flow of steam to said branch pipe lines, branch conduits opening out of the branch pipe lines and communicating 60 with the vertical cylinders of the T-shaped steam tubes, and a discharge steam pipe communicating with the discharge pipes.

OWEN F. McENANEY.
